CALLING DEVICE

Herbert F. Obergfell, River Forest, Ill., assignor
to Associated Electric Laboratories, Inc., Chi-
cago, Ill., a corporation of Delaware

Application April 7, 1934, Serial No. 719,430

14 Claims. (Cl. 179—90)

The present invention relates in general to calling devices, or impulse senders, of the type commonly used in automatic telephone systems to enable the subscribers in such systems to transmit 5 digital series of impulses to effect the proper control over the automatic switches.

The object of the invention is the provision of an improved calling device of the foregoing character. A particular object is the provision of a 10 calling device which is especially suitable for use at the subscribers' stations in a party line automatic telephone system which is equipped for measured service, as set forth in detail in the pending application of E. S. Peterson, S. N. 15 684,477, filed August 10, 1933.

The various features of the invention will be pointed out hereinafter as the constituent parts thereof are described and their operation explained, reference being made for this purpose to 20 the accompanying drawing.

Referring to the drawing, Fig. 1 is a circuit diagram of the essential parts of a system in which the invention may be used.

Fig. 2 is a front view of the dial or calling device, one of which is installed at each party line station.

Fig. 3 is a rear view of the dial, showing the spring assembly.

Figs. 4 to 9, inclusive, are views of the spring 30 operating cam members and associated parts. Of these latter figures, Figs. 4, 6, and 8 are top views of the cam carrying members disassembled, while Figs. 5, 7, and 9 are, respectively side views of the same parts.

In Fig. 1, two party line subscribers' stations on 35 a ten party line are represented by A1 and A10. The line terminates at the exchange in a line switch LS of standard type. Associated with the line at the exchange are ten meters of which 40 two, M1 and M10, are shown. There is also a meter selecting switch S.

The line switch LS and line switches associated 45 with other party lines of the kind disclosed herein have access to first selectors of standard type by way of trunk circuits such as the trunk circuit T. This trunk circuit includes a number of relays and a small stepping switch S1.

The first selector and other switches are not 50 shown herein as they may be of any suitable type, such as the well known Strowger switches in common use. The system should, however, include means for operating the subscribers' meters on successful calls. Meter operation may be by the well known "booster" method, as shown in U. S.

Patent No. 1,186,823, in which booster battery is momentarily applied to the release trunk when the called party answers. The circuits shown are arranged for this method of operation, but can readily be revised to take care of meter operation by other methods, as, for example, by the well known reverse current method.

The calling device will now be described in detail, after which the manner in which it operates in the party line measured service system illustrated will be explained. This dial or calling device is similar mechanically to the usual dial in common use in automatic telephone systems at the present time, except that it has eleven finger holes instead of ten and transmits a maximum 5 of eleven impulses instead of ten impulses. The arrangement of the finger holes and the numbering thereof is shown in Fig. 2.

The calling device is conveniently manufactured as a modification of the calling device disclosed in U. S. Patent No. 1,642,822, granted September 20, 1927. The calling device shown in the above patent has only ten finger holes but the spacing between the first finger hole and the finger stop is double the spacing required for the 10 transmission of one impulse. In fact, when the digit one is pulled, the impulse cam is rotated 15 sufficient to transmit two impulses, when the digit 5 is pulled, the cam is rotated sufficient to transmit six impulses, and so on, the digit nought corresponding to a rotation sufficient for eleven impulses. The calling device is, however, provided with a cam which rotates with the number wheel, which is effective to move the impulse springs 20 out of range of the impulse cam during the last 25 transmission of one impulse thereof, when otherwise it would transmit the last impulse. One impulse is 30 always omitted, therefore, at the end of each series, so that the actual number transmitted always 35 corresponds to the digit pulled on the dial. 40

Now, the only modification which is required in the above described calling device to make it transmit a maximum of eleven impulses is the omission of the cam which moves the impulse springs out of range of the impulse cam. When this cam 45 is left off no impulses are omitted or cancelled. The mechanism of the eleven hole calling device, therefore, may be the same as shown in the patent except that the cam referred to is not provided. 50

In order to make the finger holes correspond to the modified mechanism a different number wheel is provided such as is shown in Fig. 2. It will be seen that this number wheel has eleven 55 finger holes, the additional hole being provided,

referring to the dial of the patent, in the space between the finger stop and the No. 1 finger hole. The digit number card behind the dial is so arranged that this new finger hole bears the digit 1. 5 The digits assigned to the other ten finger holes are all rotated one space in a clockwise direction, so that the old No. 1 finger hole becomes No. 2, No. 2 becomes No. 3, and so on. This leaves one finger hole after No. 0 to which the "digit" 11 is 10 assigned, all as shown in the drawing, Fig. 2. Of course, an arbitrary designation can be used in the eleventh finger hole if desired.

The eleven hole dial described in the foregoing is further provided with certain sets of 15 contact springs and cams for operating them which are required in the party line metering system and these additional parts will now be described, reference being made to Fig. 3 and Figs. 4 to 9, inclusive. Fig. 3 shows a rear view of the 20 complete calling device including not only the additional parts referred to but also the old parts. This is necessary in order that the complete arrangement may be understood.

The contact springs normally provided consist of impulse springs 16 and 17, and a set of 25 shunt springs 15, as may be seen by reference to the hereinbefore mentioned patent. These springs are clamped between bushings as shown and lie in a plane above the back of the calling 30 device where they can be operated by the cams provided for that purpose. The additional springs provided are a pair consisting of springs 10 and 11 and another pair consisting of springs 18 and 19. There is also a member 12 formed somewhat 35 like a contact spring. All these springs and member 12 are assembled along with the impulse springs and shunt springs above referred to. Springs 10, 11, and 16 and member 12 are insulated in the usual way, but spring 19 is assembled 40 alongside of impulse spring 17 without any intervening insulation. The four extra springs and the member 12 are offset so that the ends thereof lie in a plane above the plane of the impulse and shunt springs. The member 12 supports a pivoted cam 13 for operating contact 45 spring 11.

Referring now also to Figs. 8 and 9, the reference character 31 indicates the usual tapered hub 50 which is used to attach the upper end of the helical main spring to the finger wheel shaft. The detailed construction of the hub and the associated parts is shown and described in U. S. Patent No. 1,615,311, granted January 25, 1927. It is sufficient to state here that the hub 31 fits over the 55 end of the main finger wheel shaft and rotates with it. To the hub 31 is attached a member 27 having a portion thereof formed as a cam 30 for operating the shunt springs 15. A similar cam 53 is shown in Patent No. 1,642,822. The cam 53 60 shown in this patent is, however, not provided, for reasons previously explained, and in place thereof the member 27 is formed with two projections 28 and 29.

Referring now to Figs. 6 and 7, the reference 65 character 22 indicates a disc having two ears 23 and 24. The disc 22, as shown in Fig. 3, rests on the projections 28 and 29 and the openings in ears 23 and 24 correspond to the openings in the projections 28 and 29. Rivets in these openings 70 hold the parts together. The disc 22 carries two cams 25 and 26 for operating the cam 13, Fig. 3. There is also a pin 33 projecting from the upper surface of disc 22. This pin lies on the circle 75 described by the holes 34 in member 20 next to be described.

The member 20 is shown in Figs. 4 and 5 and can also be seen clearly in Fig. 3. It comprises a disc-like portion corresponding in size to disc 22, and a cam 21, the latter being provided for operating spring 18. Member 20 is secured to disc 22 by means of a small machine screw which passes through member 20 into a threaded hole in disc 22. The cam 21 has an enlarged portion with an opening therein so that the screw can be reached with a screw driver. When the member 20 is secured in place the pin 33 lies in one of the openings 34.

The functions of the parts just described may now be considered more in detail. It is intended that the springs 10 and 11 shall be closed only if 15 the digit 11 is pulled on the dial and that when closed these springs will remain closed until the dial returns to normal. When the digit 11 is rotated in a counter-clockwise direction, Fig. 3, 20 and the parts are so designed that as the finger of the operator approaches the finger stop cam 23 engages cam 13. Further movement of the finger dial causes cam 26 to rotate cam 13 on its pivot with the result that when the dial has 25 been rotated to the limit the cam 13 will be standing substantially perpendicular to the end portion 14 of spring 11. For safety, the parts should be adjusted so that cam 13 is moved slightly past dead center, as it is required to stay in this 30 position while the dial is returning. The operation of cam 13 obviously closes spring 11 against spring 10. As the dial returns the cam 25 will engage cam 13 just before the dial reaches normal and the further movement of the dial to normal 35 moves cam 13 to its original position as shown in Fig. 3.

If any digit of a lower value than the digit 11 is pulled on the dial the cam 13 will not be operated, for cam 26 will not then reach it. 40

The springs 18 and 19 are adapted to be closed by cam 21. To this end the spring 18 may be provided with a bushing which can be engaged by the cam. This cam presses spring 18 against spring 19 when the dial is pulled down and also 45 when it returns. As will presently appear, however, it is only when the dial is returning that the springs 18 and 19 have any effect. The member 20 is adjustable so that cam 21 can be made to engage springs 18 during any desired impulse 50 interval while the dial is returning to normal. As shown in Fig. 3 member 20 is set so that cam 21 closes the springs during the last or eleventh impulse interval. By loosening the screw, member 20 can be raised and rotated to position pin 33 55 in a different hole 34. This circular row of holes and the cooperating pin are provided as an accurate and easy way of adjusting the cam to any desired position.

Referring now to Fig. 1, it will be assumed that 60 the subscriber at station A10 desires to make a call, and the ensuing operations will be described.

Station A10 is one of ten stations on the party line having conductors 41 and 42 extending to the automatic exchange. As mentioned hereinbefore there are ten meters at the exchange which correspond respectively to the ten stations. When any station makes a call a necessary operation to be performed before the call can be completed is the selection of the proper meter in 65 order to prepare to record the call. The selection is preferably accomplished preliminary to setting up the desired connection and is taken care of by the subscribers themselves through the medium of dialling an additional digit. This 70 75 80 85 90 95

extra digit is the digit 11. It may be stated that all the subscribers on the line have instructions to the effect that the digit 11 must be prefixed to all regular exchange numbers.

5 When the receiver is removed at station A10, the transmitter is bridged across the line in the usual way, resulting in the closure of a circuit over line conductors 41 and 42 for the line relay 50 of the rotary line switch LS. The operation 10 of the line switch is well known and hence need not be explained. It will suffice to say that the operation of the line relay causes the line switch to select an idle trunk leading by way of a trunk circuit such as T to a first selector. If the trunk 15 on which the wipers 53—56 are standing is idle, it is at once seized by the operation of switching relay 51. If this trunk is busy the wipers are rotated by stepping magnet 52 until an idle trunk is found, the idle condition being determined by 20 the test wiper 55, which picks up ground potential from busy test contacts to keep magnet 52 operating and to shunt relay 51.

Assuming that the trunk comprising conductor 150—153 is the first trunk found idle, when the 25 wipers arrive at the contacts associated with this trunk the rotation will cease and the switching relay 51 will operate, disconnecting the line conductors 41 and 42 from the line relay 50 and from ground, respectively, and extending them by way of wipers 53 and 56 to trunk conductors 150 and 153, respectively. As a result of the foregoing line relays 103 and 102 of the trunk circuit T operate over the line from the calling station. Relay 103 closes a circuit at armature 116 for 30 release relay 104. The latter relay, on energizing, prepares various circuits which will be described later, and also, at armature 120, places ground on the release trunk conductor 152. This completes the usual holding circuit for switching relay 51 of the line switch.

40 The line relay 102 is connected to ground through the secondary winding of the dial tone transformer shown and hence as soon as the connection is extended to the trunk circuit by the line switch the calling subscriber will receive a tone indicating that he can commence dialing the desired number. As before stated, the digit 11 must be prefixed to all numbers and therefore the dial is first operated in accordance with this 50 digit.

When the digit 11 is pulled the dial is rotated in a clockwise direction, see Fig. 2, and the cam assembly as shown in Fig. 3 will be rotated in a counter clockwise direction. At the beginning 55 of the rotation cam 21 forces spring 18 momentarily against spring 19 but this is of no effect for springs 10 and 11 are not closed. As the rotation is completed, cam 26 engages cam 13 and operates it as described hereinbefore, with the 60 result that spring 11 is forced into engagement with spring 10 and held there. As can be seen from the circuit drawing this prepares a circuit for grounding the upper line conductor 41 by spring 18 on the return movement of the dial. It 65 may be mentioned also that at this point that the rotation of the dial also results in the rotation of cam 30 which permits the shunt springs 15 to close and short circuit the transmitter and the receiver.

70 When the dial returns to normal the impulse cam is rotated. This cam momentarily separates spring 16 from spring 17 eleven times, thus producing the well known circuit interruptions or "impulses" by means of which the numerical 75 switching operations are controlled at the ex-

change. Line relays 102 and 103 both respond to these interruptions, relay 104, however, remaining in operated position because it is slow to release. The first time relay 103 falls back it closes a circuit for stepping magnet 134 in switch 5 S1 which extends by way of grounded armature 116, armature 119, armature 132, and winding of magnet 134 to battery. Switch S1 therefore advances one step. Line relay 102 falls back with relay 103 and closes a circuit for slow acting 10 relay 107, the circuit extending from ground by way of armature 103, armature 113, armature 117, and winding of relay 107. Relay 107 operates and remains energized throughout the time relay 102 is responding to the interruptions of the 15 line circuit. Relay 107 closes a circuit for relay 108 which operates and locks itself to the release trunk conductor 152 at armature 131. Relay 108 also opens the original circuit of the stepping magnet 134 at armature 132 and the circuit of 20 relay 107 at armature 130. However, the contacts at these two armatures have already been shunted by the operation of armatures 129 and 126 of relay 107. Line relay 103 therefore continues to send impulses to magnet 134. It will be 25 noticed that off normal springs 136 are closed at the first step of switch S1, but relay 107 holds open the circuit of release magnet 133 at armature 127.

At the same time that it sends impulses to switch S1, the line relay 103 sends impulses to 30 the meter selecting switch S over the following path: Ground at 130 or 126, armature 115, armature 118, armature 122, conductor 151, wiper 54, conductor 44, and winding of stepping magnet 5 to battery. The switch S is therefore advanced 35 along with switch S1. On the first step of switch S the off normal contacts 3 are closed. The circuit of release magnet 4 is however held open by slow acting relay 6, which operates in parallel with magnet 5 and holds up during impulses.

40 The relays operate as described with the result that after ten interruptions of the line circuit have been produced ten impulses will have been transmitted to magnets 134 and 5 and switches S1 and S will have advanced to their tenth positions. 45 The impulse cam next produces the eleventh interruption. At this time cam 21 closes springs 18 and 19, these springs remaining closed during the time impulse springs 16 and 17 are opened by the impulse cam. The conditions during the 50 eleventh interruption are therefore modified by the grounding of the upper line conductor 41. As a result relay 102 alone responds, relay 103 being held up over the temporarily grounded line conductor 41.

When relay 102 falls back alone it closes a circuit for relays 105 and 106 in parallel, said circuit extending from ground by way of armature 116, armature 114, and windings of relays 105 and 106 to battery. Relay 106 is slow to pull up and cannot operate responsive to a standard length impulse such as is delivered by relay 102 under control of the dial. Relay 105 operates, opens the impulsive circuit for magnet 5 of the meter selecting switch S at armature 122, and locks itself 60 over a circuit including ground, armature 127, armature 124, and armature 123. A branch of the locking circuit extends from the upper end of the upper winding of relay 105 by way of armature 125, wiper 135 of switch S1, tenth contact in bank, 70 and winding of relay 101 to battery. Relay 101 energizes and locks itself to the grounded release trunk conductor 152 at armature 111. At armature 110 relay 101 supplies ground to the locking circuit of relay 105, as the original ground is to 75

be shortly removed by the falling back of relay 107.

Relay 101 also disconnects the line relays 102 and 103 at armatures 102 and 112 and connects the incoming trunk conductors 150 and 153 to automatic trunk conductors 155 and 156, respectively, extending to the first selector. The line and release relays (not shown) of the selector accordingly energize and the latter supplies a holding ground to the release trunk conductor 152. At the trunk circuit the deenergization of line relay 103 is followed by the deenergization of relay 104 which breaks the circuit of relay 101. The latter relay, on falling back, closes a circuit for the release magnet 133 of the switch S1. S1 is therefore restored to normal, whereupon the circuit of release magnet 133 is broken at off normal springs 136.

Relays 101, 103, and 105 remain energized throughout the connection, the first two being locked to release trunk conductor 152, and the last named relay being locked to ground at armature 110 of relay 101. It will be recalled that the energization of relay 105 opens the impulsing circuit to magnet 5 of the meter selecting switch S at armature 122. At the same time a circuit is closed at armature 121 which extends ground to conductor 151 by way of resistance 160. The resistance is high enough to prevent the operation of magnet 5, but the relay 6 is held up. The meter selecting switch therefore remains with its wiper 2 standing on the tenth contact, with the result that meter M10 is connected to conductor 43 and to release trunk conductor 152.

The calling subscriber at station A10 may now dial the digits in the desired number, and the first selector which has been taken for use together with other switches will be operated in the usual way to complete the desired connection and signal the called subscriber. When the called subscriber answers, a booster battery is momentarily inserted in the circuit of the release trunk conductor 152. The increased voltage operates the connected meter M10 to register the call. When the subscriber at station A10 replaces his receiver the bridge across the line is broken and the connection is released in the usual manner. The removal of ground from release trunk conductor 152 permits the switching relay of the line switch LS to restore and permits the energized relays in the trunk circuit T to fall back. Relay 101 disconnects ground from conductor 151, whereupon relay 6 falls back. This closes a circuit for release magnet 4 of switch S, which restores the switch to normal, springs 3 opening in normal position to open the circuit of magnet 4.

It will be understood that although in the calling device at station A10 the cam 21 is set in the position shown in the drawing, Fig. 3, with the pin 33 in the tenth hole, at the other stations the cams corresponding to cam 21 are set differently, in fact, each cam has a different setting corresponding to the number of the associated station. At the No. 1 station, for instance, the cam is set with pin 33 in the first hole. The operations which take place when the subscriber at station A1 makes a call will now be briefly explained. The station apparatus at A1 is not shown in detail but is the same as at station A10 except for the different setting of cam 21.

The results which follow the removal of the receiver are the same as previously described. When the preliminary digit 11 is pulled in the dial the cam such as 13 is set in the described manner 75 in order to prepare for grounding the negative

line 41 on the return movement. When the dial returns, relays 102 and 103 fall back responsive to the first line interruption and the latter relay delivers an impulse to switch S1 and also an impulse to switch S, advancing these switches one step each. During the second interruption cam 21 closes springs 18 and 19, grounding line conductor 41 and thus preventing line relay 103 from falling back. Relay 105 is therefore energized and locked up, opening the impulsing circuit to 10 magnet 5 of switch S. Ground is supplied to relay 6 through resistance 160. During the third interruption springs 18 and 19 are not in engagement as cam 21 has passed on, so that the third and succeeding interruptions operate the line relays 102 and 103 in the normal way. The latter relay resumes the transmission of impulses to switch S1 but sends no more impulses to switch S because of the fact that relay 105 has operated. Switch S therefore is left standing with its wiper 2 in engagement with the first contact, thus connecting up the No. 1 meter. Since eleven interruptions are produced, and since the effect of one is lost by holding up relay 103, just ten impulses will be delivered to switch S1, which is thus advanced to the tenth contact in its bank. Wiper 135 at this point closes the circuit of relay 101 and the ensuing operations are the same as described.

From the foregoing the manner in which the corresponding meters are selected responsive to calls from the other stations on the line will be readily understood. Each subscriber always prefixes the digit 11. Eleven interruptions are always produced therefore, effective to control the trunk circuit T, and during one interruption, which one depends on the station calling, the negative line is grounded to operate relay 105 and stop the meter selecting switch S. Switch S1 continues to operate responsive to the remaining interruptions and delays the operation of relay 101 until the preliminary series of interruptions is finished.

In any measured service system some consideration must be given to the possibility that some subscriber will attempt to put through a call without going through the required operations, with the object of defrauding the company. The mechanical construction of the calling device herein shown positively requires that the digit 11 be prefixed to each number called. Unless this digit is prefixed the cam 13 is not operated, and unless cam 13 is operated no grounding of the line 41 can occur during the impulse transmission. Without such grounding of the line relay 105 cannot be operated and relay 101 cannot be operated to connect the line through to the first selector. In order to prevent tampering with the calling device the instrument may be sealed, or preferably, a drop of sealing wax may be placed over the screw which retains cam 21 in position. Thus any attempt by a subscriber to change the setting of cam 21 so as to charge his calls to a different subscriber can be defeated, or at any rate, will be detected on the next inspection.

However, a subscriber may attach wires to the line terminals of his instrument and to the ground terminal and attempts to simulate the operation of the calling device, applying the ground during some random interruption or during some interruption which will not result in selection of his meter, if the setting of the meter cam 21 is known. The fact that switch S1 must receive ten impulses makes it rather difficult to obtain any 75

results this way, as any momentary cessation of the impulses for a longer period than the normal spacing will let relay 107 fall back, releasing switch S1. As an added precaution relay 106 is provided. This relay, it will be recalled, is slow to pull up and will not energize in the normal operation of the system. However, in attempting to get through the trunk circuit T by manipulating wires, the operator is liable to ground the line for too long a period and any substantial increase in the length of the impulse delivered to relay 105 results in the energization of relay 106 in parallel with it. Relay 105 is thus prevented from locking up because relay 106 is slightly slow to release and will hold the locking circuit open at armature 124 until after it is opened at armature 123. Unless relay 105 is locked up, relay 101 cannot be operated, even if the switch S1 is successfully stepped around, and the line cannot be extended through to the first selector.

The invention having been described, the particulars as to which the protection of Letters Patent is desired will be pointed out in the appended claims.

25 What is claimed is:

1. In a calling device of the type which includes a setting member and in which impulses are transmitted upon the restoration of the setting member, a contact member, means responsive to the operation of said setting member in accordance with certain digits for transmitting impulses without actuating said contact member, means responsive to the operation of said setting member in accordance with another digit for actuating said contact member, means for retaining said contact member in actuated position, and means effective upon the completion of the restoration of the setting member for restoring said contact member.

40 2. In a calling device, a dial, a shaft on which said dial is supported, a pair of contact springs, a pivoted member for operating said springs when rotated, said pivoted member being arranged and adapted to tend to remain in its normal position until rotated and to remain in its rotated position until restored, a cam on said shaft for rotating said pivoted member responsive to a predetermined movement of the dial, and another cam on said shaft for restoring said pivoted member upon the return of the dial to normal.

55 3. In a calling device, a main shaft on which a dial is carried, a pivoted member supported adjacent said shaft, a cam on said shaft for rotating said member when the dial is turned a predetermined amount, a spring contact member actuated by said pivoted member, the said members being so related that the pressure of said spring member holds the other member in actuated position, and another cam on said shaft for restoring said pivoted member upon the return of the dial to normal.

60 4. In a calling device, a rotatable dial, a spring for returning said dial after it has been rotated, an impulse sender actuated a number of times during the return movement depending on the extent of the rotation, and a contact device actuated only when the said dial is rotated sufficient to send the maximum number of impulses.

70 5. In a calling device, a setting member, a pair of contacts closed at the end of a predetermined movement of said setting member, means for holding said contacts closed during the restoration of said setting member, a pair of contacts closed only at a predetermined point in the

restoration of said setting member, and a circuit including said pairs of contacts in series.

6. In a calling device, a rotatable dial, a spring for returning said dial after it has been rotated, impulse sending means operated a number of times during the return movement of the dial depending on the extent of the rotation, a second impulse sending means operated only once during the return movement, and adjustable means having a number of fixed positions, for varying the point in the return movement at which the operation of said second sending means takes place according to the position in which said adjustable means is placed.

10 7. In a calling device, a rotatable dial, a spring 15 for returning said dial after it has been rotated, impulse sending means operated a number of times during the return movement of the dial depending on the extent of the rotation, a second impulse sending means operated only once 20 during the return movement, two circuits over which the two sending means send impulses, respectively, and means whereby the second circuit is rendered effective only upon a particular amount of rotation of the said dial.

25 8. In a calling device, a rotatable dial, a shaft for said dial, means for returning the dial and shaft to normal after the dial is rotated, impulse sending mechanism driven by gears from said shaft during the return movement of the dial, 30 additional impulse sending mechanism operated directly by a member attached to said shaft during the return movement, and means for securing said member in any one of a number of set positions to predetermine the point in the return 35 movement at which the said additional sending mechanism is operated.

9. In a calling device, a rotatable dial, means for returning said dial after it has been rotated, impulse springs, means for separating said 40 springs a number of times during the return movement of the dial depending on the extent of the rotation, and means also operated during the return movement to ground one of said springs at a time when it is separated from the 45 other spring.

10. In a calling device, a rotatable dial, means for returning said dial after it has been rotated, impulse springs normally closed, means for separating said springs a number of times during 50 the return movement of the dial depending on the extent of the rotation, impulse springs normally open, and means for closing said springs once during the return movement, the closing taking place concurrently with a particular opening of the said first mentioned springs.

11. In a calling device, a rotatable dial, means for returning said dial after it has been rotated, a first impulse contact, means for actuating said first contact during the return movement of the 60 dial a number of times which depends on the extent of the rotation, a second impulse contact, and means for actuating the second impulse contact during the return movement only after at least one actuation of the first contact has been 65 effected and terminated, and for terminating the said actuation of the second impulse contact prior to the final actuation of the first contact.

12. In a calling device, a rotatable dial, means for returning said dial after it has been rotated, a 70 first impulse contact, a second impulse contact, means for actuating the first contact during the return movement to send a number of impulses which depends upon the extent of the rotation, means for actuating the second contact coincident 75

with one of the said actuations of the first contact, and selecting means for predetermining the actuation of the first contact with which the actuation of the second contact coincides.

5. 13. In a calling device, a first contact, a second contact, means for producing a series of actuations of the first contact, means coincidentally effective for producing an actuation of the second contact, and means adjustable to any one 10 of a number of fixed positions for predetermining, according to its adjusted position, the position in

the series of actuations of the first contact to be occupied by the actuation of the second contact.

14. In combination, means for generating a series of impulses, means coincidentally effective for generating another impulse during said series, 5 and means adjustable to any one of a number of fixed positions for predetermining, according to its adjusted position, the position in the series to be occupied by said other impulse.
